CLAIM

The ornamental design for an interior rack of an appliance with backlit feature, as shown and described.

DESCRIPTION

FIG. 1 is a perspective view of an interior rack of an appliance with backlit feature separate from the appliance.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines in the drawings illustrate portions of the interior rack of an appliance with backlit feature or environmental structure which form no part of the claimed design.

1 Claim, 3 Drawing Sheets
